SCALE FOR COMPUTING CALORIES OF FOOD

Samuel J. Koch, % Korex Industries, 821 Malcolm
Road, Burlingame, Calif. 94010

Filed Jan. 20, 1975, Ser. No. 542,440

Term of patent 14 years

Int. Cl. D10—04

U.S. Cl. D10—91

Fig. 1

Fig. 2

Fig. 3

Fig. 6

Fig. 4

Fig. 5

Fig. 7

FIG. 1 is a front elevational view of a scale for computing calories of food showing my new design;

FIG. 2 is a rear elevational view thereof;

FIG. 3 is a top plan view thereof;

FIG. 4 is a left side elevational view thereof;

FIG. 5 is a right side elevational view thereof;

FIG. 6 is a top plan view thereof with the tray in the storage position on the rear of the scale;

FIG. 7 is a rear elevational view with the tray in the storage position.

I claim:

The ornamental design for a scale for computing calories of food, as shown and described.
